ATTORNEY

UNITED STATES PATENT OFFICE.

FRIEDRICH HERRMANN, OF NEW YORK, N. Y.

LIFE-PRESERVER.

SPECIFICATION forming part of Letters Patent No. 370,538, dated September 27, 1887.

Application filed January 31, 1887. Serial No. 225,953. (No model.)

To all whom it may concern:

- Be it known that I, FRIEDRICH HERRMANN, a citizen of the United States, residing at New York, in the county of New York, State of New York, have invented certain new and useful Improvements in Life-Preservers, of which the following is a specification, reference being had therein to the accompanying drawings.
- 10 My invention relates to an improvement in life-preservers, the object being to provide a device of this character which shall be simple and economical in construction, and which shall be capable of being worn beneath the clothing without any inconvenience to the wearer; and with such ends in view my invention consists in certain novel features of construction, as will be hereinafter fully described, and pointed out in the claims.
- 15 In the accompanying drawings, Figure 1 represents a view in front elevation of my improved life-preserved. Fig. 2 is a view in side elevation of one of the air-chambers inflated.
- 20 A represents the two air-chambers, constructed, preferably, of canvas or other fabric so treated as to be impervious to air, and secured to the support B, made of canvas or other suitable material. The chambers A are each constructed of the two compartments a b, leading from one into the other, in the form of a bellows, for the purpose of allowing them to be folded when not inflated. The two chambers A are connected by means of the pipe C, which is connected at its middle point with the pipe D, having at its upper end the mouth-piece e, by means of which the two compartments A are inflated.
- 25 To the support B is secured a strap, E, adapted, when the life-preserved is in position on the body of the wearer, to pass around the back of the neck and assist in retaining it in position. To the ends of the support B are secured the straps F, adapted to pass around the back of the wearer, and through the slots or openings d in the support, after which they are tied, as shown in Fig. 1, for the purpose of securing the device in position.
- 30 G represents a spring-clasp designed to be attached to the pipe D for the purpose of preventing the escape of the air through such pipe when the chambers A are inflated.
- 35 The operation of the device is as follows: The life-preserved is placed in position by passing the strip E around the neck and the straps F around the back through the openings d in the support B, and tying them, as shown in Fig. 1, the air-chambers A fitting opposite the chest. The said chambers A are then inflated by blowing through the pipe D, 60 the air passing through the pipe C into the compartments a and b. After said chambers have been filled with air the spring-clasp G is attached to the pipe D, compressing it and effectually preventing the escape of the contained air. When it is desired to empty the life-preserved of the confined air, the clasp G is removed from the pipe D, allowing the escape of the air through the mouth-piece e.
- 40 It will now be understood from the above 70 description that my invention is exceedingly simple in construction, can be manufactured at a small cost, and may be worn beneath the clothing, the bellows-like construction of the chambers allowing them to fold flatly, and in 75 thickness not much greater than an ordinary garment. The pipe D, leading upward to within a short distance of the mouth, may be hidden from view by the outer garment of the wearer.
- 45 Having fully described my invention, what I claim as new, and desire to secure by Letters Patent, is—
1. As a new article of manufacture, a life-preserved adapted to be worn beneath the 80 clothing and constructed with two communicating air-chambers secured to a support, a pipe for filling the chambers and connected to the pipe through which said chambers communicate, and straps for holding the device in 85 position, substantially as set forth.
2. A life-preserved constructed with two communicating air-chambers each of which is formed with two compartments, a pipe connecting the two chambers, and a pipe connected with said latter pipe and through 90
- 95

which said chambers are inflated, substantially as set forth.

3. The life-preserved hereinbefore described and constructed with two communicating air-chambers secured to a support, the pipe C, connecting the said chambers, pipe D, connecting with said pipe C and through which said chambers are inflated, and a spring-clasp adapted to fit on said pipe D,

substantially as and for the purpose described.

In testimony whereof I affix my signature in presence of two witnesses.

FRIEDRICH HERRMANN.
